Primary Examiner — Darlington Ly(74) *Attorney, Agent, or Firm* — Reising Ethington, P.C.(57) **CLAIM**

The ornamental design for a cyclometer for e-bikes, as shown and described.

DESCRIPTION

FIG. 1 is a top, front, and left side perspective view of a cyclometer for e-bikes embodying our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a rear, top, and right side perspective view thereof. The broken lines in the drawings illustrate portions of the cyclometer for e-bikes that form no part of the claimed design.
